(57) **CLAIM**

The ornamental design for a frameless cork board, as shown.

DESCRIPTION

FIG. 1 is a frontal isometric view of my frameless cork board;

FIG. 2 is a rear isometric view thereof;

FIG. 3 is a front elevational view thereof;

FIG. 4 is a left side elevational view, taken from a position to the left of FIG. 3 and looking towards the right;

FIG. 5 is a right side elevational view, taken from a position to the right of FIG. 3 and looking towards the left;

FIG. 6 is a top plan view, taken from a position generally above FIG. 3 and looking downwardly;

FIG. 7 is a bottom plan view, taken from a position generally below FIG. 3 and looking upwardly; and,

FIG. 8 is an enlarged rear elevational view thereof.
